CLAIM

The ornamental design for a docking station, as shown and described.

DESCRIPTION

FIG. 1 is a left, top and front perspective view of a docking station showing my new design;
FIG. 2 is a right, bottom and rear perspective view of the docking station of FIG. 1;
FIG. 3 is a front view of the docking station of FIG. 1;
FIG. 4 is a rear view of the docking station of FIG. 1;
FIG. 5 is a left side view of the docking station of FIG. 1;
FIG. 6 is a right side view of the docking station of FIG. 1;
FIG. 7 is a top view of the docking station of FIG. 1; and,
FIG. 8 is a bottom view of the docking station of FIG. 1.
The broken lines in the figures illustrate portions of the article that form no part of the claimed design.

1 Claim, 8 Drawing Sheets
